WILLIAM A. HEILMANN, OF NEWARK, NEW JERSEY, ASSIGNOR TO THE R. NEUMANN HARDWARE CO., A CORPORATION OF NEW JERSEY.

BAG-FRAME.

1,220,224.

Specification of Letters Patent.

Patented Mar. 27, 1917.

Application filed November 25, 1916. Serial No. 133,287.

To all whom it may concern:

Be it known that I, WILLIAM A. HEILMANN, a citizen of the United States, residing at Newark, in the county of Essex and 5 State of New Jersey, have invented certain new and useful Improvements in Bag-Frames; and I do hereby declare the following to be a full, clear, and exact description of the invention, such as will enable others 10 skilled in the art to which it appertains to make and use the same, reference being had to the accompanying drawings and to characters of reference marked thereon, which form a part of this specification.

15 The present invention has reference, generally, to improvements in frames for traveling bags, satchels, and the like; and, the invention has reference, more particularly to that class of bag-frames, known in the art 20 as L-frames, that is, a bag-frame, comprising a pair of hinged frame-sections, each frame-section being L-shaped in cross-section, one of the frame-sections having a lock mounted upon its outer and upper surface, 25 and the other frame section having, in the ordinary practice, secured upon the outer face of its vertical member a hasp-plate provided with right-angled hasp-lugs adapted to engage the lock when the frame-sections 30 are closed.

With frames of this construction, when covered with leather, to sew the bag-body thereto, at the place where the hasp-plate is secured upon the outer face of the frame-section, in the manner above described, it is necessary with machine-sewing to arrest the sewing operation and to throw the line of stitching away from the frame, out of alignment with the main line of stitching, in 40 order to pass around the hasp-plate, all of which is objectionable on account of the loss of time during the sewing operation, as well as the danger of striking the hasp-plate with the needle, aside from the fact that in 45 fitting the leather of the mouth of the bag-body about the hasp-plate, a bulky and unsightly appearance will result at that point upon the outer face of the frame-section.

The present invention, therefore, has for 50 its principal object to take the cheaper construction of L-frame, cover the same with leather and adapt the hasp-plate and its hasp-lugs to one of the frame-sections in such a manner, so that the mouth of the bag-

body can be readily sewed thereto by means 55 of machine-stitching or sewing in one continuous operation, and when finished to all appearances the finished bag having the appearance of the more expensive bags, known in the trade as "English" or "sewed-in" bags. 60

A further object of the present invention is to save cost, time and labor during the sewing operation and to provide a neat and improved appearance by reason of the eveners and continuity of the machine-stitching and doing away with the possibility of exposing a portion of the raw edge of the mouth of the bag at the point where it has to be lapped around the hasp-plate when the latter is secured upon the outer vertical face 70 of the frame-section.

Other objects of the present invention not at this time more particularly enumerated will be clearly understood from the following detailed description of my present invention. 75

With the various objects of the present invention in view, the said invention consists, primarily, in the bag-frame and hasp-plate therefor, mounted with relation to one of 80 the frame-sections in the manner herein-after more fully set forth; and, the invention consists, furthermore, in the novel arrangements and combinations of the various devices and parts, as well as in the details 85 of the construction of the same, all of which will be more fully described in the following specification and then finally embodied in the clauses of the claims which are appended to and which form an essential part 90 of the said specification.

The invention is clearly illustrated in the accompanying drawings, in which:—

Figure 1 is a top or plan view of fragmentary portions of the two frame-sections 95 of the usual L-shaped construction, one of which is provided with a hasp-plate and hasp-lugs in the manner of the present invention, said view showing in connection with the leather-covered frame-sections, 100 fragmentary portions of the mouth of the bag-body, sewed thereto by continuous and uninterrupted straight lines of machine-stitching or sewing, the two frame-sections being represented in their partially opened 105 relation.

Fig. 2 is a view of the inner face of one of the said frame-sections provided with

the hasp-plate, looking in the direction of the arrow α in said Fig. 1.

Fig. 3 is a transverse vertical section, on an enlarged scale of the frame-section represented in said Fig. 2, said section being taken on line 3—3 in the said Fig. 2.

Fig. 4 is a similar sectional representation of the frame-section provided with a modified arrangement of mounting the hasp-plate.

Similar characters of reference are employed in all of the above described views, to indicate corresponding parts.

In the said drawings, the reference-characters 1 and 2 indicate the usual metal bag-frame sections, the frame-section 1 being provided with the usual vertical right-angled member 3, see Fig. 1 of the drawings, and the frame-section 2 being similarly provided with the usual vertical right-angled member 4, as illustrated in all of the figures of the drawings. Referring now to Figs. 1, 2 and 3 of the said drawings, it will be seen that the said frame-sections 1 and 2 have a suitable covering 5 of leather or any other suitable material which extends also around the right-angled members 3 and 4 of the respective frame-sections, each covering or envelop 5 terminating in outwardly and forwardly extending sewing flanges, as 6, extending along the marginal edge-portions 7 of the frame-sections, and over which the mouth-portions 8 of the leather or other bag-body are placed and secured thereto by means of a continuous line of machine stitching or sewing, as 9. Suitably secured upon the upper face of the said covered frame-section 1 is the usual bag-lock, as 10, with which the hasp-lugs 13 of a hasp-plate 11 are adapted to enter into locked engagement when the two frame-sections 1 and 2 are brought into their closed relation.

As shown more particularly in Fig. 3 of the drawings, the frame-section 2 is pierced, as at 15, the covering 5 being correspondingly pierced, as at 16 and 17.

The hasp-plate 11 is secured upon the inner covered face of the member 4 of the frame-section 2 by means of rivets 14, or other suitable fastening means, the hasp-plate being provided with upwardly extending arms or posts 12 which are passed into and through the said perforations or holes 15, 16 and 17. As illustrated in said Fig. 2, said arms or posts 12 are provided with the previously mentioned hasp-lugs 13. In order to bring the outer face-portions of the said arms or posts 12 vertically in alinement with the outer face of the member 4 of the frame-section 2, each arm or post 12 is preferably bent, as at 18, whereby a neat construction and an artistic finish is the result.

If desired, the hasp-plate 12 may be mounted upon the inner face of the member

4 of the frame-section 2, before the frame-section is provided with the covering 5, in which case the said covering is finally arranged entirely over the face of the said hasp-plate 12, as will be clearly understood 70 from an inspection of Fig. 4 of the drawings.

From the foregoing description of the present invention it will be seen that by the novel arrangement of the hasp-plate with relation to the metal bag-frame of L-shaped cross-section, I have produced a frame of cheap construction in the nature of a "sewed-in" frame, to which the mouth of the bag-body can be sewed by stitching, continuously from one end of the bag-frame to the other end thereof, in a straight line, thereby producing a neat, quick and easy method of sewing, which saves time, labor and expense, and at the same time produces 80 a bag of neat appearance, and one in which the mouth of the bag-body is sewed fast at all points to the frame-sections of the bag-frame.

Of course, I am fully aware that changes 90 may be made in the general arrangements and combinations of the several devices and parts, as well as in the details of the construction of the said parts, without departing from the scope of the present invention 95 as set forth in the foregoing specification. Hence, I do not limit my present invention to the exact arrangements and combinations of the several devices and parts as described in the said specification, nor do I confine 100 myself to the exact details of the construction as illustrated in the accompanying drawings.

I claim:—

1. A bag-frame comprising a pair of 105 hinged frame-sections of angular cross-section, a covering upon each frame-section, each covering having a sewing flange extending in an outward direction from the outer marginal edge-portion of each frame-section, said flanges being adapted to be located beneath the edge-portion of the mouth of a bag-body and further adapted to receive a continuous straight line of stitching closely to the said outer marginal edge of 110 each frame-section, combined with a hasp-plate secured to one of said frame-sections having hasp-lug carrying posts extending from the upper surface-portion of said frame-section at points back of the outer 115 face of the angular member connected with the main member of said frame-section.

2. A bag-frame comprising a pair of frame-sections, each frame-section consisting of a main body-member and a depending member integrally connected therewith, so as to provide a frame-section of L-shaped cross section, and a hasp-plate secured to one of said frame-sections having hasp-lug carrying posts extending from the upper 120 125 130

surface-portion of said frame-section at points back of the outer face of the said depending member, each post being provided with an angularly bent portion extending 5 forwardly in a direction toward the marginal edge formed by the angle of the said main body-member and the said depending member, all arranged so as to bring the outer face-portions of the said posts vertically in alinement with the outer face-portion 10 of the said depending member.

3. A bag-frame comprising a pair of frame-sections, each frame-section consisting of a main body-member and a depending member integrally connected therewith, so as to provide a frame-section of L-shaped cross section, said main body-member being provided with openings, and a hasp-plate 15 secured to the inner surface portion of one of said members, hasp-lug carrying posts connected with said hasp-plate, said posts extending into and through the said openings and extending from the upper surface portion of the said main body-member of 20 said frame-section, each post being provided with an angularly bent portion extending forwardly in a direction toward the marginal edge formed by the angle of the said main body member and the said depending member, all arranged so as to bring the outer surface portions of the said posts vertically 25

in alinement with the outer face-portions of the said depending member.

4. A bag-frame comprising a pair of frame-sections, each frame-section consisting of a main body-member and a depending member integrally connected therewith, so as to provide a frame-section of L-shaped cross section, said main body-member being provided with openings, and a hasp-plate 35 secured to the inner surface portion of said depending member, hasp-lug carrying posts connected with said hasp-plate and extending from the upper surface portion of the said main body-member of said frame-section, each post being provided with an angularly portion extending forwardly in a direction toward the marginal edge formed by the angle of the said main body-member and the said depending member, all arranged so as to bring the outer face portions 40 of the said posts vertically in alinement with the outer face-portions of the said depending member. 50

In testimony, that I claim the invention set forth above I have hereunto set my hand this 23rd day of November, 1916. 55

WILLIAM A. HEILMANN.
